REMOTE CONTROL APPARATUS

Earl M. Allen, Swissvale, Pa., assignor to The Union Switch & Signal Company, Swissvale, Pa., a corporation of Pennsylvania

Application July 1, 1932, Serial No. 620,443

10 Claims. (Cl. 246—3)

My invention relates to remote control apparatus, and has for an object the provision of novel and improved apparatus for controlling railway traffic governing devices such as switches and signals from a distant point.

One feature of my invention is the provision of means for governing traffic movements over a railway track switch under given conditions, if and only if the switch is unlocked, and for governing traffic movements over the switch, under other conditions, if and only if the switch is locked.

I will describe one form of apparatus embodying my invention, and will then point out the novel features thereof in claims.

The accompanying drawings, Figs. 1^a and 1^b, when placed end to end with Fig. 1^a on the left, constitute a diagrammatic view showing one form of apparatus embodying my invention.

Referring to the drawings, the reference character W designates a stretch of single track railway which is provided with passing tracks Y and Z, the ends of which are connected with stretch W at switches F¹ and F². Each of these switches may be biased to its normal position, in which it is shown in the drawings, by some suitable means which may, for example, be of the well known spring type. Each of these switches may be manually movable to its reverse position by suitable means not shown in the drawings, and may also be movable to its reverse position by a train going over the switch in the trailing direction, that is, switch F¹ may be movable to its reverse position by a train going over it from track Y to stretch W, and switch F² may be movable to its reverse position by a train going over it from track Z to stretch W.

Rails 1 and 1^a of stretch W and of tracks Y and Z are divided by means of insulated joints 2 into sections A—B, B—C, B^a—C^a, C—D and D—E. A track circuit is shown for each of the sections B—C to D—E, inclusive, and includes a track battery 3 connected across the rails adjacent one end of the section, and a track relay 4 designated by the reference character R with a distinguishing exponent and connected across the rails adjacent the other end of the section.

Signals, each of which is designated by the reference character S with a distinguishing exponent, govern traffic movements in both directions over switches F¹ and F². Signals S² and S³ govern traffic movements in the trailing direction over switch F¹ from tracks Z and Y, respectively, to stretch W, and signals S¹ and S^{1a} govern traffic movements in the opposite or fac-

ing direction over switch F¹ from stretch W to tracks Z and Y, respectively. Similarly, signals S⁴ and S⁵ govern traffic movements in the trailing direction over switch F² from tracks Z and Y, respectively, and signals S⁶ and S^{6a} govern traffic movements in the opposite or facing direction over switch F² from stretch W to tracks Y and Z, respectively. As here shown, each of the signals S is of the color light type, although it is to be understood that my invention is not limited to this particular type of signals. Signals S¹ and S⁶ are shown having a red or stop lamp R, and two proceed lamps comprising a green lamp G indicating "clear" and a yellow lamp Y indicating "caution". Each of the signals S^{1a} and S^{6a} is provided with only a caution lamp Y and a stop lamp R. Each of the signals S², S³, S⁴ and S⁵ is provided with a green lamp G indicating "clear", and a red lamp R indicating "stop".

Circuits and other parts of the apparatus are shown for controlling switch F² and signals S⁴, S⁵, S⁶ and S^{6a}. Switch F¹ and signals S¹, S², S^{1a} and S^{6a}, respectively, are controlled by exactly similar circuits and other parts of the apparatus, which are omitted from the drawings in order to simplify the patent application.

Lock bar b is rigidly secured to switch F² for engagement by a dog a, by means of which the switch may be locked in its normal position. Dog a is actuated by a motor G which may be of any suitable type but which, as here shown, is an electric motor having an armature 27 and a field winding 28. In conjunction with dog a, motor G actuates a contact 25 which is closed at all times except when dog a reaches its final position out of engagement with bar b; a contact 26 which is closed at all times except when dog a reaches its final position for locking bar b; a contact 36 which is closed only when dog a is in its final position for locking bar b; and a contact 43 which is closed only when dog a is in its final position out of engagement with bar b. Movement of motor G is controlled by a relay L so that, when relay L is deenergized, motor G actuates dog a into position to lock bar b, and when relay L is energized, motor G actuates dog a out of engagement with bar b.

A switch circuit controller of the usual type for signal selection purposes is operated by switch F², and has a contact 34 which is closed only when switch F² is in its normal position, and a contact 39 which is closed only when switch F² is in its reverse position.

Switch F² also actuates a second circuit controller, commonly known as a point detector, which has contacts 29 and 35 each of which is

closed only if the switch points are in their proper condition while the switch is in its normal position.

- 5 A manually operable push button contact P^F is located adjacent switch F^2 for use of trainmen when it is desired that the switch shall be unlocked to permit of its being manually reversed for a train movement over the switch in the facing direction from stretch W to track Z .
- 10 10 Relay L is controlled in part by a relay v having neutral contacts 19 and 31 and polar contacts 20 and 32 . Relay v is energized by current of normal or of reverse polarity controlled from a remote point such, for example, as a despatcher's office. As here shown, a manually operable lever V having a normal position n , a left reverse position f , and a right reverse position r , actuates pole-changing contacts 17 and 18 for controlling the normal and reverse energization of relay v
- 15 20 by a source of current not shown in the drawings, but which has terminals x and o . Relay L is also controlled in part by a locking relay M^6 which is associated with signals S^6 and S^{6a} , and in part by a locking relay M^{4-5} which is associated with signals S^4 and S^5 .
- 25 A slow pick-up relay T at times controls the energization of relays M^{4-5} and M^6 upon the lapse of a measured period of time after the associated signals are controlled to indicate "stop", or after track relay R^3 becomes energized.

30 Each of the signals S is controlled, at least in part, by a relay designated by the reference character H with a corresponding exponent.

- 35 Each relay H is controlled in part by relay v . Relays H^6 and H^{6a} for controlling signals S^6 and S^{6a} , respectively, are controlled by polar contact 32 of relay v in its normal position, whereas relays H^4 and H^5 for controlling signals S^4 and S^5 , respectively, are controlled by polar contact 32 of relay v in its reverse position. Relays H are also controlled in part by lock relays M , by track relays R , and by the circuit controllers which are actuated by motor G and by switch F^2 .

- 40 A push button circuit controller contact P^S , having a front point and a back point, is located adjacent signal S^5 for use of the trainmen in clearing signal S^5 for traffic movements in the trailing direction from track Y to stretch W .

- 45 In the drawings, the contacts operated by the various relays or by the various other control devices are identified by numbers, such numbers having distinguishing exponents when such contacts are shown elsewhere than adjacent the control device by which they are operated. The exponent for each of these contact numbers comprises the reference character and exponent for the respective control device. Contact 16^{R^3} , for example, shown in the circuit for relay T , has an exponent R^3 which comprises the reference character R and its exponent 3 for track relay R^3 which operates contact 16^{R^3} .

- 50 Having described, in general, the form of apparatus which is shown on the accompanying drawings, I will now describe in detail the operation of the apparatus.

- 55 As shown in the drawings, all parts are in their normal condition, that is, the track sections are unoccupied, switches F^1 and F^2 are locked in their normal positions by the engagement of a dog a with a bar b , lever V is in its normal position, and relays v , H , L , and T are deenergized. With relays H deenergized, the red lamp of each signal is lighted, by a circuit passing through the back point of a contact 4 of the associated relay H , to

5 indicate "stop". With the track sections unoccupied, the relays R are energized. With relays H deenergized and with relays R energized, each of the relays M is energized. The circuit by which relay M^{4-5} is energized is a stick circuit passing from terminal x of the source of current, through back contacts 10^{H^4} and 11^{H^5} , front point of contact 13 of relay M^{4-5} , contact 14^{R^3} , and the winding of relay M^{4-5} to terminal o . Both a pick-up and a stick circuit are closed for relay M^6 . The 10 pick-up circuit passes from terminal x , through contact 5 of relay H^{6a} , contact 5 of relay H^6 , contact 6 of relay R^4 , contact 8 of relay R^3 , and the winding of relay M^6 to terminal o . The stick circuit for relay M^6 follows the path just traced for 15 the pick-up circuit as far as contact 5 of relay H^6 , and thence passes through the front point of contact 9 of relay M^6 , and the winding of relay M^6 to terminal o .

20 I will assume that, with all parts thus in their normal condition, the despatcher desires to permit a westbound train, that is, a train moving from right to left as shown in the drawings, to proceed over switch F^2 in its normal position. He will therefore operate lever V to its left reverse position f , causing relay v to be energized in the normal direction by its circuit passing from terminal x , through contact 17 of lever V in its f position, winding of relay v , and contact 18 of lever V in its f position, to terminal o .

25 With relay v energized in the normal direction and with switch F^2 occupying its normal position, a circuit is closed for energizing relay H^6 , passing from terminal x , through front contact 31 of relay v , contact 32 or relay v in its left position, contact $33^{M^{4-5}}$, contacts 34 and 35 actuated by switch F^2 , contact 36 actuated by motor G , contact 37 of relay R^2 , contact 38 of relay R^3 , and the winding of relay H^6 to terminal o .

30 With relay H^6 energized, contact 4 opens at its back point, thus extinguishing lamp R of signal S^6 . Contact 4 then completes at its front point the lighting circuit for lamp Y of signal S^6 . It is to be understood that if signal S^3 were displaying a proceed indication, lamp Y of signal S^6 would be extinguished and lamp G of this signal would be lighted as controlled by means which, in order to simplify the application, I have omitted from the drawings. That is to say, the control of signal S^6 is interrelated with the control of signal S^3 50 in the manner customary in standard block signaling practice. The energization of relay H^6 causes its back contact 5 to open both the pick-up and the stick circuit previously traced for relay M^6 , thereby causing relay M^6 to become deenergized.

35 A train, upon entering section $D-E$, will cause relay R^4 to become deenergized and open its contact 6 in the pick-up circuit for relay M^6 which is, however, already open at contact 5 of relay H^6 .

40 When the train enters section $C-D$, it causes relay R^3 to become deenergized and open, at its contact 8 , the circuit previously traced for relay H^6 . Relay H^6 being thereby deenergized, its contact 4 opens, at its front point, the circuit for lamp Y of signal S^6 , and again closes, at its back point, the circuit for lamp R of signal S^6 . The deenergization of relay R^3 causes contact 8 of this relay to open, at another point, the pick-up circuit traced for relay M^6 . The deenergization of relay R^3 causes relay M^{4-5} to be deenergized on account of contact 14^{R^3} being opened.

45 When the train leaves section $C-D$, relay M^6 again becomes energized by its pick-up circuit previously traced. When relay M^6 closes its front 75

contacts, slow pick-up relay T will become energized by a circuit passing from terminal x, through contacts 10^{H4} and 11^{H5}, back point of contact 13 of relay M⁴⁻⁵, contact 15^{M6}, contact 16^{R3}, and the winding of relay T to terminal o. Upon the lapse of a measured period of time after this circuit becomes closed, relay T will close its front contacts, thereby completing a pick-up circuit for relay M⁴⁻⁵, passing from terminal x, through contacts 10^{H4}, 11^{H5}, 12^T, and 14^{R3}, and the winding of relay M⁴⁻⁵ to terminal o. Relay M⁴⁻⁵, upon becoming energized, completes its stick circuit previously traced through the front point of its contact 13, and deenergizes relay T by opening the circuit for relay T at the back point of contact 13.

I will assume that the despatcher returns lever V to its normal position, and that after the train moves beyond the stretch of track shown in the drawings, he again clears signal S⁶ by operating lever V to its f position, that a westbound train then proceeds past signal S⁶ over switch F² in its normal position, and that before the train leaves section C—D a second train enters section D—E. When the first of these two trains leaves section C—D, relay M⁶ will not be picked up by its circuit through contact 6 of relay R⁴, because relay R⁴ will now be deenergized by the second train in section D—E. Relay T will, however, now be energized by a second circuit passing from terminal x, through contact 5 of relay H^{6a}, contact 5 of relay H⁶, back point of contact 9 of relay M⁶, contact 16^{R3}, and the winding of relay T to terminal o. Upon the lapse of a measured period of time after this circuit becomes closed, relay T will close its front contact 17^T, thus completing a branch path around contact 6 of relay R⁴ and causing relay M⁶ to become energized by a pick-up circuit which is otherwise the same as the pick-up circuit previously traced for this relay. At the same time, contact 12^T completes the pick-up circuit previously traced for relay M⁴⁻⁵, causing this relay to also become energized. Relay M⁶, upon becoming energized, opens, at the back point of its contact 9, the second circuit traced for relay T, thus causing relay T to become deenergized.

I will next assume that all parts of the apparatus are again in the normal condition, and that the despatcher now wishes a westbound train to proceed from stretch W to track Z over switch F² reversed. He may, therefore, stop the train at signal S⁶ by having this signal continue to display the stop indication. He may next instruct a trainman by telephone that the train is to proceed onto track Z.

The despatcher will then operate lever V to its right reverse position r, causing relay v to be energized in the reverse direction. With relay v energized in the reverse direction, a pick-up circuit is completed for relay L, passing from terminal x, through contacts 19 and 20 of relay v, front point of contact 21^{M6}, and the winding of relay L to terminal o. With relay L energized, the reverse operating circuit is completed for motor G, passing from terminal x, through the front point of contact 24 of relay L, contact 25 operated by motor G, armature 27 of motor G, front point of contact 30 of relay L, field winding 28 of motor G, and contact 29 of switch F² to terminal o. Motor G will thereupon withdraw dog a from engagement with bar b.

The trainman will then manually move switch F² to its reverse position.

The despatcher will now operate lever V to its

left reverse position f, causing relay v to become energized in the normal direction. With relay v now energized in the normal direction, a circuit is completed for relay H^{6a}, passing from terminal x, through contact 31 of relay v, contact 32 of relay v in its left position, contact 33^{M4-5}, reverse contact 39 of switch F², contact 40 of relay R¹, and the winding of relay H^{6a} to terminal o. Relay H^{6a}, upon becoming energized, opens, at the back point of its contact 4, the circuit for lamp R of signal S^{6a}, thus extinguishing this lamp. Relay H^{6a} then closes, at the front point of its contact 4, the circuit for lamp Y of signal S^{6a}, causing this lamp Y to now be lighted. Relay H^{6a}, upon becoming energized, also opens, at its back contact 5, both the pick-up and the stick circuit for relay M⁶, causing this relay to become deenergized.

The train, upon entering section C—D in response to the lighting of lamp Y of signal S^{6a}, causes relay R³ to become deenergized, which then opens, at its contact 14^{R3}, the stick circuit for relay M⁴⁻⁵, causing this relay to become deenergized.

When the train has passed over switch F², a trainman will manually restore this switch to its normal position. Since relay L has already been deenergized by the opening of contact 20 of relay v when this relay was energized in the normal direction, switch F², upon being returned to its normal position, completes, at its contact 29, the normal operating circuit for motor G, passing from terminal x, through the back point of contact 24 of relay L, contact 26 operated by motor G, armature 27 of motor G, back point of contact 30 of relay L, field winding 28 of motor G, and contact 29 of switch F² to terminal o.

When the train leaves section C—D, relays M⁶, T, and M⁴⁻⁵ will again become energized in the order named, as previously described.

I will assume that all parts of the apparatus are again in their normal condition, and that the despatcher, instead of stopping a westbound train at signal S⁶, has transmitted a written train order to the train to stop at switch F² preparatory to moving over switch F² reversed although signal S⁶ is displaying a proceed indication. Accordingly, when the train has passed signal S⁶, and has stopped at switch F² and a trainman has communicated this fact to the despatcher, the despatcher will operate lever V to its right reverse position, thus energizing relay v in the reverse direction. On account of signal S⁶ having been controlled to display a proceed indication when the train entered section D—E, relay M⁶ is now deenergized. The trainman will depress push button contact P^F, thus completing a second pick-up circuit for relay L, passing from terminal x, through contacts 19 and 20 of relay v, contact P^F, back point of contact 21^{M6}, and the winding of relay L to terminal o. Both relay M⁶ and relay M⁴⁻⁵ having become deenergized in the manner described in connection with other train operations, relay L, upon becoming energized, now completes, at its contact 23, its own stick circuit passing from terminal x, through contact 22^{M4-5}, contact 23, and the winding of relay L to terminal o. Motor G will now unlock switch F² as previously described.

I will now assume that switch F² and all other parts of the apparatus adjacent switch F² are again in their normal condition, that an eastbound train enters track Z, approaching signal S⁴, and that the despatcher desires to permit this train to move over switch F² to stretch W. He

will therefore operate lever V to its *r* position, causing relay *v* to become energized in the reverse direction. With relay *v* energized in the reverse direction, relay *L* will become energized by its 5 pick-up circuit first traced. Motor *G* will thereupon unlock switch *F*² as previously described, and will complete, at its contact 43, a circuit for energizing relay *H*⁴, passing from terminal *x*, through contact 31 of relay *v*, contact 32 of relay *v* in its 10 right-hand position, contact 41 of relay *R*³, contact 42^{M6}, contact 43 operated by motor *G*, the front point of push button contact *P*⁸, and the winding of relay *H*⁴ to terminal *o*. The energization of relay *H*⁴ causes lamp *R* of signal *S*⁴ to be 15 extinguished and lamp *G* of this signal to become lighted. The energization of relay *H*⁴ also causes its contact 18^{H4} to open the stick circuit which is now energized for relay *M*⁴⁻⁵. Relay *M*⁴⁻⁵ thereupon becomes deenergized, completing the stick 20 circuit previously traced for relay *L*.

The train, upon entering section C—D, deenergizes relay *R*³ which then opens, at its contact 41, the circuit just traced for relay *H*⁴. Relay *H*⁴, being thus deenergized, causes signal *S*⁴ 25 to again display a stop indication. Switch *F*² being unlocked, the train, while moving over the switch, will force it to the reverse position.

When the train leaves section C—D, the pick-up 30 circuit first traced for relay *T* will again become closed, causing relay *T* to become energized and, after the lapse of a measured period of time, to again complete the pick-up circuit traced for relay *M*⁴⁻⁵.

I will next assume that switch *F*² and all other 35 parts of the apparatus adjacent switch *F*² are again in their normal condition, that an eastbound train enters track Y, approaching signal *S*⁵, and that the despatcher desires to permit this 40 train to move over switch *F*² in its normal position to stretch W. The despatcher will therefore again operate lever V to its reverse position *r*, thus causing relay *v* to become energized in the reverse direction and energize relay *L*, which then causes 45 motor *G* to unlock switch *F*². The trainman will depress push button contact *P*⁸, causing this contact to complete, at its back point, a circuit for energizing relay *H*⁵ which is the same as the circuit previously traced for relay *H*⁴ except that 50 it includes the back point of contact *P*⁸ instead of the front point of this contact.

As the train now proceeds through section C—D, the operation of the apparatus will be 55 similar to that described when a train proceeds from track Z over switch *F*², except that switch *F*² will now remain in its normal position while the train is passing over it.

The operations of switch *F*¹ and signals *S*¹, *S*^{1a}, *S*² and *S*³ are exactly similar to the operations 60 described for switch *F*² and signals *S*⁶, *S*^{6a}, *S*⁵, and *S*⁴, respectively.

For normal train operation, signal *S*¹ will be 65 cleared for an eastbound train which will then proceed over switch *F*¹ locked in its normal position, and will then move onto track Z. Signal *S*⁴ will also be cleared for this train which will now move over switch *F*² unlocked, and will reverse switch *F*² while passing from track Z to stretch W. Similarly, a westbound train will, 70 in normal operation, move over switch *F*² locked in its normal position after having been given a proceed indication by signal *S*⁶, and will then move from track Y, while signal *S*³ is displaying a proceed indication, over switch *F*¹ unlocked, 75

forcing switch *F*¹ to the reverse position during movement over the switch.

Assuming that the despatcher desires to pass a fast eastbound train around a slow eastbound train, he may, if there is sufficient time, have the slow train stop, and then, after manual reversal of switch *F*¹, move onto track Y. The flagman on the rear of the slow train would then return switch *F*¹ to its normal position. The fast train can then be permitted to move over switch *F*¹ 10 in its normal position, past signal *S*¹ displaying a proceed indication, and then onto track Z, and past signal *S*⁴, and over switch *F*² to track W. The slow train can then proceed from track Y to stretch W. By this method of operation, the 15 fast train would proceed over switches *F*¹ and *F*² without stopping, and at the usual rate of speed.

Another method of passing a fast eastbound train around a slow eastbound train would, if the 20 trains were close together, be to permit the slow train to move over switch *F*¹ in its normal position to track Z. The flagman on the rear of the slow train would then manually reverse switch *F*¹ for the fast train to move onto track Y. The 25 head brakeman of the slow train could depress push button *P*⁸ for clearing signal *S*⁵ for the fast train to proceed over switch *F*² in its normal position. By this method of operation, the fast train might be required to slightly reduce speed for 30 passing over switch *F*¹ reversed, but would not be required to stop at any time while passing around the slow train.

From the foregoing description and the accompanying drawings, it follows that one form of apparatus embodying my invention comprises a track switch which is biased to a normal position, and which may be of the well known spring switch type; an electrically operated device for locking this switch in its normal position; a manually controlled traffic governing device for authorizing traffic movements in the facing direction over the switch while the switch is in its normal position, if and only if the switch is locked; and a manually controlled traffic governing 35 device for authorizing traffic movements in the trailing direction over the switch, if and only if the switch is unlocked.

I have described for a few typical traffic movements the operation of one form of apparatus 40 embodying my invention. From these descriptions and from the accompanying drawings, the operation of the apparatus for every other possible traffic movement may be readily determined.

Although I have herein shown and described 45 only one form of remote control apparatus embodying my invention, it is understood that various changes and modifications may be made therein within the scope of the appended claims without departing from the spirit and scope of my 50 invention.

Having thus described my invention, what I 55 claim is:

1. In combination, a railway track, a second railway track, a track switch interconnecting said first and second tracks and biased to a normal position for directing traffic movements along said first track only but operable to a reverse position by a train moving from said second track to said first track, manually controllable means for 60 electrically locking and unlocking said switch in said normal position, means manually controlled for governing traffic movements over said switch in the normal position if and only if said switch is locked, and other means manually controlled 65

for governing traffic movements over said switch from said second track to said first track if and only if said switch is unlocked.

2. In combination, a railway track switch, manually controlled means for at times locking said switch and for at other times electrically unlocking said switch, a traffic governing device manually controlled for permitting traffic movements over said switch if and only if said switch is locked, and a second traffic governing device manually controlled for permitting traffic movements over said switch if and only if said switch is unlocked.

3. In combination, a track section containing a manually movable railway track switch which is spring-biased to its normal position, a motor-operated lock which when operated to its normal position locks said switch in the normal position and which when operated to the reverse position switch, a second signal for governing traffic movements in the trailing direction over said switch, a second signal for governing traffic movements in the opposite direction over said switch, a stick locking relay associated with said first signal, means for deenergizing said stick locking relay if said first signal is controlled to display a proceed indication or if said track section is occupied, means for again energizing said stick relay only upon the lapse of a measured period of time after said first signal is controlled to indicate "stop", a manually controlled instrument having a normal and a reverse position, means controlled by said instrument in its reverse position for operating said lock to its reverse position, means for retaining said lock in its reverse position as long as said stick locking relay is deenergized, means controlled by said instrument in its reverse position for clearing said first signal if and only if said lock is reversed, and means controlled by said instrument in its normal position for clearing said second signal if and only if said lock is in its normal position.

4. In combination, a section of railway track including a switch, a signal for governing traffic movements in a given direction over said switch, a second signal for governing traffic movements in a second direction over said switch, a stick locking relay, a stick circuit for said relay which is opened when said first signal is controlled to display a proceed indication, a pickup circuit for again energizing said relay only upon the lapse of a measured period of time after said first signal is controlled to display a stop indication and only if said track section is unoccupied, means for locking said switch, means controlled by said stick locking relay for retaining said switch in its unlocked condition if said stick locking relay is deenergized, and means controlled by said stick locking relay for clearing said second signal only if said stick locking relay is energized.

5. In combination, a section of railway track including a switch, a signal for governing traffic movements over said switch, an approach track section for said signal, a track circuit for each of said track sections including a track relay, an approach locking relay, a signal relay, means controlled by a front contact of said signal relay for clearing said signal, a pickup circuit for said approach locking relay controlled by a front contact of each of said track relays, a stick circuit for said approach locking relay controlled by a back contact of said signal relay, and means controlled by said approach locking relay for controlling said switch.

6. In combination, a section of railway track including a switch, a signal for governing traffic movements over said switch, an approach track section for said signal, a track circuit for each of said track sections including a track relay an approach locking relay, a signal relay, means controlled by a front contact of said signal relay for clearing said signal, a pickup circuit for said approach locking relay controlled by a front contact of each of said track relays, a stick circuit for said approach locking relay controlled by a back contact of said signal relay, means controlled by said approach locking relay for controlling said switch when said approach locking relay is energized, and manually controlled means for controlling said switch when said approach locking relay is deenergized.

7. In combination, a railway track switch, means manually controlled from a remote point for at times locking said switch and for at other times electrically unlocking said switch, and a traffic governing device manually controlled from said remote point for permitting traffic movements over said switch if and only if said switch is unlocked.

8. In combination, a railway track switch, a manually controllable lever having a normal position and a first and a second reverse position, means controlled by said lever in its normal position or in its first reverse position for locking said switch, means controlled by said lever in its second reverse position for unlocking said switch, a first and a second signal for governing traffic movements over said switch, means controlled by said lever in its first reverse position for clearing said first signal, and means controlled by said lever in its second reverse position for clearing said second signal.

9. In combination, a railway track switch, a signal for governing traffic movements over said switch, a manually controllable instrument, a locking device manually controllable for at times locking said switch, means controlled by said manually controllable instrument for clearing said signal when and only when said switch is unlocked, and means controlled by said manually controllable instrument for preventing an operation of said locking device to lock said switch until the lapse of a given period of time after said signal has been caused to indicate stop.

10. In combination, a railway track switch, a signal for governing traffic movements in a given direction over said switch, a second signal for governing traffic movements in an opposite direction over said switch, an instrument manually controlled for at times clearing said first signal, a second manually controlled instrument, means controlled by said second manually controlled instrument for at times clearing said second signal when and only when said switch is unlocked, a locking device manually controlled for at times locking said switch, means controlled by said first instrument for preventing an operation of said locking device to unlock said switch until the lapse of a given period of time after said first signal has been caused to indicate "stop", and means controlled by said second instrument for preventing an operation of said locking device to lock said switch until the lapse of a given period of time after said second signal has been caused to indicate "stop".

August 13, 1935.

EARL M. ALLEN.

It is hereby certified that error appears in the printed specification of the above numbered patent requiring correction as follows: Page 5, first column, line 20, claim 3, before "switch" insert the words unlocks said; and in same line 20, strike out the word "second"; same page, second column, line 5, claim 6, after "relay" insert a comma; and line 44, claim 9, strike out the word in; and that the said Letters Patent should be read with these corrections therein that the same may conform to the record of the case in the Patent Office.

Signed and sealed this 17th day of September, A. D. 1935.

(Seal)

Leslie Frazer
Acting Commissioner of Patents.
